CONTRAROTATING TURBOJET ENGINE
HAVING INDEPENDENT BEARING SUPPORTS FOR EACH TURBOCOMPRESSOR

Eugene L. Hunsaker, Manhattan Beach, Calif., assignor, by mesne assignments, to General Electric Company, Schenectady, N. Y., a corporation of New York

Application October 8, 1949, Serial No. 120,247

1 Claim. (Cl. 60—35.6)

1

My invention relates to axial flow compressor-turbines of the gaseous combustion type, and more particularly to an improved compressor-turbine suitable for use in aircraft driven at high subsonic or supersonic speeds.

When combustion turbines are utilized in such aircraft, high airflow capacity is necessary to increase the engine thrust coefficient and to decrease the external drag coefficient. At present, the required airflows are obtained by the use of high blade speeds in axial flow compressors of compressor-turbine combinations used to drive the high speed airplanes.

High blade speeds result in large values of centrifugal stress on the rotating blades as

Stress (centrifugal) =

$$\frac{(\text{blade tip speed})^2 \times \text{blade length} \times \text{constant}}{\text{compressor diameter}}$$

This stress relationship in the compressor limits the blade length and hence limits flow area and capacity for a given diameter of compressor. A directly coupled turbine will also have large values of blade tip speed, and hence high values of centrifugal stress. The physical characteristics of the hot turbine blades particularly limits blade length, and hence airflow rate for a given turbine diameter.

It is an object of the present invention to provide a compressor-turbine combination which is capable of higher air capacities than are conventionally obtainable with compressors using high blade speeds and supersonic air velocities relative to the blades.

It is another object of the present invention to provide an improved compressor-turbine combination having relatively low blade tip speeds.

It is still another object of the invention to provide a compressor-turbine combination having relatively long blade lengths, with a consequent significant increase in airflow capacity.

It is a further object of the present invention to provide a compressor-turbine combination of the combustion type suitable for driving aircraft at high subsonic and supersonic speeds.

A still further object of the invention is to provide an improved compressor-turbine in which high compression ratios can be produced in a single compressor stage, while maintaining high air capacity and relatively low blade tip speeds.

Another object of the present invention is to provide higher compressor efficiencies in compressor-turbines operating at supersonic relative velocities.

Briefly, the present invention involves a com-

2

bustion-turbine engine having contra-rotating compressor blade discs directly driven by contra-rotating turbine blade discs. The terms compressor rotor blades and turbine rotor blades are used in the conventional sense of meaning blades having the proper contours for rotating blades of compressors and turbines of compressor-turbine engines; whereas the terms compressor counter-rotating blades and turbine counter-rotating blades are used in an unconventional sense indicating only that the counter-rotating blades have respective proper contours for compressor stator blades and turbine stator blades, even though rotating.

15 My present invention provides for a compressor-turbine in which the compressor blades of the stator type are contra-rotated with respect to the compressor-rotor blades, so that the compressor-rotor speed can be decreased for a given 10 overall stage pressure ratio. I prefer to drive the contra-rotating compressor blades by a turbine disc having turbine rotor blading thereon, working in conjunction with a contra-rotating disc having turbine stator type blades thereon, 15 this disc being connected to drive the compressor-rotor blading. The compressor rotor blading is preferably directly connected to a turbine disc having turbine stator type blades thereon, so that both compressor and turbine comprise contra-rotating blading. In this way the tip speeds of both compressor and turbine blading are relatively low, and an increased air capacity is obtained for a given engine diameter.

In this design, the stator type blades are contra-rotated with respect to the rotor type blades and the blade boundary layer energized through this relative rotation. This suppresses separation of the flow from the stator type blades and improves efficiency.

20 25 30 35 40 My invention will be more fully understood by reference to the drawing, showing in diagrammatic form, a longitudinal sectional view of a combustion turbo-jet engine embodying a preferred form of the present invention.

45 Referring to the drawing, an outer turbine casing 1 is provided having at one end an airflow inlet 2 and at the opposite end, a jet outlet 3. Attached to casing 1 just inside of the airflow inlet, a plurality of radial guide vanes 4 are provided, extending inwardly to support an inlet cone 6, which is hollow, and in turn supports a plurality of inlet bearing hangers 7 supporting an outer race 8 of a forward bearing 9.

50 55 Inside of the jet outlet 3 a plurality of radial tail cone hangers 10 are provided, supporting a

tail cone 11. Inside of tail cone 11 a plurality of outlet bearing hangers 12 are provided, supporting the outer race 14 of a rear bearing 15. Journalled in bearings 9 and 15 is an inner cylindrical rotor 16. The forward end of the inner rotor 16 is provided with a compressor rotor disc 17 on which are mounted a plurality of compressor rotor blades 18 just rearwardly of guide vanes 4. Attached to the rear of inner rotor 16 is a turbine counter-rotating disc 19 provided with blades 20 of turbine stator type, these blades being the rearmost of the turbine assembly.

Between the compressor rotor blades 18 and the turbine stator type blades 20, inside of casing 1 and adjacent the inner surface thereof, is positioned a ring of combustion chambers 21 of any conventional type, each supplied with fuel through a fuel inlet jet 22.

Forwardly of the combustion chamber ring, attached to casing 1 and extending radially inwardly is a ring of stationary compressor outlet guide vanes 24 supporting an inner shroud 25, forming an annular space for combustion chambers 21.

Rearwardly of the combustion chambers 21, attached to casing 1 and extending radially inwardly is a ring of stationary turbine inlet nozzles 26 also supporting the inner shroud 25. Extending inwardly from shroud 25 at the guide vane and nozzle stations, are a plurality of radially arranged struts 27 and 28 supporting an outer rotor 30 rotating coaxially with inner rotor 16 on front and rear outer rotor bearings 32 and 34 respectively.

Compressor rotor blades 18 and stationary guide vanes 24 are spaced to permit insertion therebetween of a plurality of compressor stator type blades 35 attached to the forward end of outer rotor 30, by compressor counter-rotating disc 36.

Similarly at the turbine, nozzles 26 and turbine stator type blades 20 are spaced to provide for a plurality of turbine rotor blades 37 mounted on a rear rotor disc 38 of outer rotor 30. Thus both the compressor and rotor have two sets of rotating blades. As one set of blades of both compressor and turbine are shaped as rotor type blades, and since another set of blades in each unit are shaped as stator type blades, the inner and outer rotors will be contra-rotating, with both rotor and stator type blades of the compressor being driven by the turbine blades, but in opposite directions. It will be apparent to one skilled in the art that, for a given overall stage pressure ratio, the rotor speed is decreased by the use of such an arrangement. The decreased speed permits greater compressor and turbine blade length, thereby increasing air capacity for a given engine diameter.

While in order to comply with the statute, the invention has been described in language more or less specific as to structural features, it is to be understood that the invention is not limited to the specific features shown, but that the means and construction herein disclosed comprise a preferred form of putting the invention

into effect, and the invention is, therefore, claimed in any of its forms or modifications within the legitimate and valid scope of the appended claim.

5 What is claimed is:

A gas turbine combination comprising an outer casing having an air entrance aperture and a jet aperture, a nose cone in said entrance aperture, a plurality of guide vanes extending from said casing and supporting said nose cone, a forward bearing supported by and within said nose cone, a tail cone in said jet aperture, a plurality of struts extending from said casing and supporting said tail cone, a rear bearing supported by and within said tail cone, an inner rotor journalled in said forward and rear bearings, a first compressor disc on the forward end of said inner rotor, a plurality of blades of compressor rotor type on said first compressor disc, a second turbine disc on the rear end of said inner rotor, a plurality of blades of the turbine stator type on said second turbine disc, a shroud positioned in said casing between said discs, supports extending from said casing and holding said shroud in said casing to provide an annular space between said shroud and casing, front and rear shroud bearings inside of and supported by said shroud, an outer rotor supported mechanically independent of said inner rotor and mounted in said latter shroud bearings to rotate concentrically with and spaced from said inner rotor, a second compressor disc on the forward end of said outer rotor, a plurality of blades of the compressor-stator type on said forward disc, said latter blades being 35 blades being positioned adjacent and to the rear of the blades on said first compressor disc, a first turbine disc on the rear end of said outer rotor, a plurality of blades of turbine rotor type on said first turbine disc, said latter blades being 40 positioned adjacent and forward of the blades on said second turbine disc, and combustion chamber means in the annular space between said shroud and said casing.
